UNITED STATES PATENT OFFICE.

CHARLES A. O'TOOLE, OF BROOKLYN, NEW YORK.

AUTOMOBILE INDICATOR.

Application filed June 23, 1921. Serial No. 479,774.

To all whom it may concern:

Be it known that I, CHARLES A. O'TOOLE, a citizen of the United States, and a resident of the city of New York, borough of Brooklyn, in the county of Kings and State of New York, have invented a new and Improved Automobile Indicator, of which the following is a full, clear, and exact description.

10 This invention relates to automobile direction indicator.

It has for an object the provision of simple, strong and efficient means readily attachable for use with any type of automobile, whereby the direction of movement of the automobile can clearly and unmistakably be indicated in both directions.

20 A further object resides in the provision of means whereby the natural position and inclination of the indicating device, when moved to exhibiting position, will clearly indicate the change in direction in addition to any signs or marks which may be placed thereon.

25 A still further object resides in the provision of means whereby this direction indicator can be as conveniently observed from the front as from the rear of the vehicle.

30 A still further object resides in the particular construction and arrangement of parts whereby the economy of manufacture and operation is reduced to a minimum, while, at the same time, the strength and efficiency of the apparatus is maintained at a maximum.

35 The invention is illustrated in the drawings, in which—

40 Figure 1 is a side view of an automobile, preferably a closed type, showing the indicator disposed on the top thereof;

Figure 2 is a vertical section taken on the line 2—2 of Figure 3;

Figure 3 is a plan view of the device;

45 Figure 4 is a vertical section taken on the line 4—4 of Figure 3; and

Figure 5 is a vertical section taken on the line 5—5 of Figure 4, showing one of the indicating devices in its elevated or exhibiting position.

The preferred form of my invention as 50 illustrated in the drawings, is applicable to any type of automobile, although I have shown it as applied to a closed type of car represented by the numeral 1 and the indicating device is represented by the numeral 55 2 located on the top or roof thereof.

This indicating device or unit comprises preferably a long narrow casing, preferably made of sheet metal and designated by the numeral 3 in Figure 4. This casing is provided along its bottom edge with a plurality of apertures, such as 4. These apertures are aligned with the normal axis of movement of a plurality of cores 5. These cores are associated with magnets, such as 6, and are disposed for movement within sheet metal cylinders 7. These magnets are wound with any desired number of turns and kind of wire adapted to give the required magnetic pull on the cores 5. The upper ends of the cylinders 7 for each magnet are adapted to be swaged or otherwise fitted into suitable apertures in a plate 10.

This plate is made of sheet metal and is preferably as shown in Figure 3, in the form of a semi-circle. The plate 10 is further provided with depressions 11 throughout its surface, each depression being provided with an aperture 12. Any moisture or water which may form or collect on the plate, may 75 pass off through these apertures.

A portion of the plate 10 acts as a closure for the top of the casing or container 3. The set of magnets 6 used and contained within the casing, are supported along their upper edges from a flange plate 13, which, by reason of a flange 14, is suitably fastened to the side wall of the casing 3.

The upper end of each core 5 is connected to a link 15, which in turn is pivotally connected to a yoke member 16 fastened to any suitable portion of an indicator plate, such as 17. As shown in Figure 3, there are five indicator plates made of sheet metal, and each one of which is provided with flange 90 portions 18 along its edges. Each of these plates 17 is pivoted on a shaft 19, which extends through suitable apertures in each

plate and is fastened at its ends in upturned flange portions 20 on each end of the diametrical edge of the plate 10.

It will be noted from a consideration of Figure 3 particularly that each of these five exhibiting or indicating plates is shaped to fill up a certain angular portion of the semi-circle and that normally these plates lie flat along the upper surface of the semi-circular plate 10. Disposed around the periphery of the plate 10 are a number of pads or cushions 21 adapted to cushion the impact of the plates 17 as they are dropped into their non-exhibiting position whenever the magnets become de-energized.

Consequently, if the indicator plate marked "Right" is elevated, as in Figure 3, the natural slope of this plate will indicate the general direction of the intent of movement without the necessity of marking the word "Right" on the plate. The same general function applies to the plate for designating a left-hand movement. In other words, whenever each plate is exhibited, it occupies a definite angular portion of the semi-circular space taken up by all of the plates, and, consequently, the mere position of the plate outside of its designation will indicate the intended operation without any markings.

In Figure 2, I have shown one end of the magnet wire, such as 22, grounded on the plate 13, and the other end of the magnet wire, such as 23, connected to a switch 24, which in turn is connected to a battery 25 grounded at 26. Each of the magnets is connected to a separate switch, all of which switches are connected in multiple to the battery 25. The switches may be of any suitable form or type and conveniently located for operation by the driver of the car. Whenever any particular switch is operated, the corresponding indicator plate is moved up into position.

A person who is familiar with this type of indicator, will at once appreciate from the angular position of the indicator just what operation is about to take place, even though he cannot see the marking on the elevated plate. This is particularly true since in this indicator device, no two plates occupy, when elevated, the same space. This particular feature is not common to any type of indicator now used, since in most cases where elevated plates or arms are used, the various arms, when elevated, occupy substantially the same space, so that the observer must see the marking on each plate to know what operation is impending.

The various movements, such as "Slow", "Back", ("Right", "Left") and "Stop" are indicated or marked on both the front and back of each plate. The device is preferably located on the top of the car whenever con-

venient, since in this position it is as easily observed from the front as from the rear, and in fact from all general forward or rearward directions.

The cores 5 it will be observed, are so disposed that in order to elevate the device, they are pulled upwardly. In other words, to elevate the plates, current is consumed to energize the magnet, the plates returning to non-exhibiting position by means of their weight and the weight of the connected parts.

This whole device is made of light, strong, sheet metal, preferably aluminum, and is exceedingly compact and rugged.

What I claim is:

1. An indicating device comprising a semi-circular plate or support adapted to be disposed horizontally on the top of an automobile with the diametrical edge preferably facing forward of the automobile, a plurality of pivoted signal arms pivoted at one end to the plate along the diametrical edge and adapted when actuated to be moved to a vertical position along this edge, the plurality of signal arms adapted to lie normally flat on the support and to cover its entire surface, each arm occupying a definite portion of the plate one of said arms shaped to extend vertically when elevated, the others of said arms shaped to point in directions to the right and to the left from the vertical when elevated, whereby the elevation of each arm will indicate a certain impending direction of movement.

2. An indicating device comprising a semi-circular plate or support adapted to be disposed horizontally on the top of an automobile with the diametrical edge preferably facing forward of the automobile, a plurality of pivoted signal arms pivoted at one end to the plate along the diametrical edge and adapted when actuated to be moved to a vertical position along this edge, the plurality of signal arms adapted to lie normally flat on the support and to cover its entire surface, each arm occupying a definite portion of the plate, one of said arms shaped to extend vertically when elevated, the others of said arms shaped to point in directions to the right and to the left from the vertical when elevated, whereby the elevation of each arm will indicate a certain impending direction of movement and a cushioning means disposed along the curved edge of the support to cushion the ends of the pivoted signal plate.

3. An indicating device including a flat semicircular support, a plurality of signal arms pivoted to said support along its diametrical edge and filling up the entire area of the support when lying normally flat thereon, an enclosed casing disposed beneath the front surface of the support adjacent the diametrical edge, a plurality of magnetic

means within said enclosed casing, and connections between said magnetic means and the signal arms whereby they may be elevated to a vertical position, each arm when elevated indicating by a character on the arm and its angular position in the semicircular area, the character of the signal one of said

arms shaped to extend vertically when elevated, the others of said arms shaped to point in directions to the right and to the left from the vertical when elevated, whereby the elevation of each arm will indicate a certain impending direction of movement.

CHARLES A. O'TOOLE.
